UNITED STATES PATENT OFFICE.

ETTORE BUGATTI, OF MOLSHEIM, FRANCE.

DEVICE FOR THE LATERAL MAINTENANCE OF THE LIFTING RODS OF FORGING HAMMERS TO PREVENT THEIR DISTORTION.

Application filed March 15, 1926, Serial No. 94,925, and in France March 16, 1925.

It has hitherto proved impossible to utilize rods of small diameter for raising the falling weight in forging or stamping hammers. In fact, by reason of the great length which must be given to such rods, the rod will be subject to distortion during the descent of the weight and the vibrations must be allowed to cease before the said weight can be again lifted.

The present invention will obviate this defect, and it consists in the use of a certain number of boards or plates of wood or other material which are threaded loosely upon the rod of the hammer and are guided by the vertical guiding members of the falling weight, said plates being spaced along the whole height representing the stroke of the said weight, so as to prevent all jarring of the rod by bearing laterally against the said guiding members.

The following description, with reference to the appended drawings which are given by way of example, show the manner in which the said invention is carried into effect.

Fig. 1 is an elevational view of the hammer, the object of the invention.

Figs. 2 and 3 are sections respectively on the lines X—X and Y—Y of Fig. 1.

As observed in the drawings, the falling weight or block *a* is guided in the known manner between the two guiding members *b*¹ and *b*² whereof one side is cut at an angle and thus engages in a recess of corresponding form in the block *a*. This latter is raised by means of a rod *c* of small diameter.

To prevent the said rod from jarring, the plates *d*¹ *d*² which are two in number in the drawings, but which may be employed in any suitable number according to the height of the apparatus, are disposed upon the rod *c* and are suitably apertured for this purpose at *e*.

The said plates, as shown in Figs. 2 and 3, are guided during the descent by the guiding members *b*¹ *b*² of the weight. The plates rest upon suitable tappets, *f*¹ for the plate *d*¹ and *f*² for the plate *d*², which are mounted on the respective guiding members *b*¹ and *b*². The said tappets have a suitable size in order to afford free passage for the plate situated underneath, as will be observed by comparing Figs. 2 and 3. By this arrangement, when the weight falls, the plate *d*²

may descend without being arrested by the tappets *f*¹ whilst it will be arrested by the tappets *f*². Obviously, if a certain number of such plates are employed, their length will diminish as they come nearer the weight *a*.

During the ascent of the weight *a*, the said plates are drawn upwardly by means of the studs *g* mounted on the weight, and will be piled up in succession on the said weight. When the weight falls, they will descend with it, each being arrested in turn by the corresponding tappet, as shown in Fig. 1. In these conditions, when the weight is at the end of its stroke, the plates will be properly distributed along the rod *c* and will prevent all vibrations of the said rod at the time of the impact.

Obviously, without departing from the principle of the invention, it is susceptible of various modifications in detail, and in particular, the invention is applicable to like devices assuring the lateral maintenance of the rod, at different points on its height, when the weight is at the end of its stroke, while allowing the said rod to move freely in the vertical direction.

What I claim is:—

1. A device for the lateral maintenance of the rods of small diameter serving to lift the falling weight in forging and stamping hammers, said device comprising suitable plates which are threaded upon the rod of small diameter and are guided between the vertical guiding members which serve to guide the said falling weight, means being provided to arrest the respective plates at different heights, whereby they will be suitably spaced along the height corresponding to the stroke of the said weight when the latter is at the bottom of the stroke.

2. A device for the lateral maintenance of the rods of small diameter serving to lift the falling weight in forging and stamping hammers, said device comprising suitable plates which are threaded upon the rod of small diameter and are guided between the vertical guiding members which serve to guide the said falling weight, tappets being distributed throughout the height representing the stroke of the said falling weight and adapted to arrest the said plates at different heights during the descent of the mass.

3. A device for the lateral maintenance of the rods of small diameter serving to lift the falling weight in forging and stamping ham-

mers, said device comprising suitable plates which are threaded upon the rod of small diameter and are guided between the vertical guiding members which serve to guide the 5 said falling weight, tappets being distributed throughout the height representing the stroke of the said falling weight and adapted to arrest the said plates at different heights

during the descent of the mass, means being provided to enable any given plate to pass 10 freely between the tappets situated above the tappet which serves to arrest the said plate.

In testimony whereof I have signed this specification.

ETTORE BUGATTI.
